UNITED STATES PATENT OFFICE.

GEORGE W. CAMPBELL, OF NEW YORK, N. Y., ASSIGNOR, BY MESNE ASSIGNMENTS, TO VICTOR TYPEWRITER COMPANY.

TABULATING DEVICE FOR TYPE-WRITERS.

No. 867,243.

Specification of Letters Patent.

Patented Oct. 1, 1907.

Application filed October 31, 1906. Serial No. 341,469.

To all whom it may concern:

Be it known that I, GEORGE W. CAMPBELL, a citizen of the United States, residing in the borough of Manhattan, city, county, and State of New York, have invented certain new and useful Improvements in Tabulating Devices for Type-writers, of which the following is a specification.

My invention refers to a tabulating device for typewriters having the purpose of freeing the carriage from the regular escapement mechanism and arresting it on certain corresponding and previously determined places of each line, and my invention comprises two stop members, one mounted on the machine frame, and the other on the paper carriage, one of said stop members having a series of stops individually adjustable on their support so as to be varied in position according to the location desired for the columns, and means including an oscillatory and sliding finger lever for shifting the stops to denominational position so that each number may be written with its digits in proper relation to those of other numbers of the same column by merely shifting a single tabulating lever, and the other stop member having a dog for engaging the aforesaid tabulating stops, vibrating between fixed stops and held and returned automatically to normal position to enable the carriage to be fed past the tabulating stops by merely operating the tabulating lever.

The invention consists in certain combinations of mechanism of the above-described character which will be more particularly set forth in the following specific description, and will be then pointed out in the claims.

In the drawings the typewriter itself is shown only as far as it is necessary to make clear the arrangement of the new device.

Figure 1 is a vertical section through the device; Fig. 2 is a view of the device seen from the key board, the carriage frame being shown in longitudinal section; and Fig. 3 is a top view of the device.

1, 2, 3, 4, 5, 6, are parts of the main frame of the typewriter. The carriage 8 may be as here shown arranged between the parts 1, 2, of the frame by means of balls 9, or otherwise supported and guided in any well known manner. Pinion 10 controlled through shaft 11 by an escapement commonly used in typewriters (not shown in Fig. 1), engages in carriage rack-bar 12 pivotally mounted within the carriage frame 8 by the pivot 15. Rack-bar 12 is held in its engaged position by spring 16, inserted between the rack-bar and a plate 20 screwed to carriage frame 8 (Figs. 1 and 3), and checked in its angular motion by pin 18 and nut 17 screwed into the rack-bar and guided in the slot 19 of plate 20. Underneath the rack-bar 12 is arranged the lever 21 bearing on its lower end roller 23

and fulcrumed on stud 22, which is preferably integral with main frame part 3. The relation of lever 21 to the rack-bar 12 is shown in two views in Figs. 1 and 2. Near roller 23 is arranged the shaft 25 journaled and sliding in the main frame parts 4, 5, 6, and having near roller 23 cone 24. It will be seen that, if shaft 25 with its cone 24 is pushed in toward roller 23, the latter will be forced to roll up the incline of the cone and lever 21 will be brought from its normal position, shown in Fig. 2, and marked by the dotted middle line A into the position marked by dotted middle line B. This will cause the upper end of lever 21 to lift rack-bar 12 up and disengage its rack from pinion 10, thus freeing the action of its propelling mechanism from the escapement control and enabling it to run freely, or under such control as may be provided in well known manner, until stopped by the special or tabulating stops now to be described. Sufficient loose motion is provided between the parts 23, 24, so that the carriage is not freed from the escapement control until the tabulating stops are properly set to arrest the carriage. The position of the cone 24 can be so varied as either to merely lift the rack-bar from its pinion allowing the carriage to run free under control of its propelling spring and the operator's hand, or as to lift the rack up against the part of the carriage frame immediately above it—in which case the operator, by varying his inward pressure upon the finger lever can cause the upper end of lever 21 to press with greater or less force upon the bar 12 as the latter slides along, thus acting as a brake.

Shaft 25 is axially held in its normal position, shown in Fig. 1, by spring 30 resting at one end against frame part 6 and on the other end against ring 31 screwed to shaft 25, which latter, resting against frame part 5, thus limits the axial motion of shaft 25 in that direction. On the right end of shaft 25 (Fig. 1), is fixed a finger lever 32 with knob 33 and with segment 36 on its upper end, which latter is provided with notches 34 (Fig. 2) adapted to engage stop finger 35 secured to frame piece 5, when lever 32 by means of knob 33 is pushed inward. The outer end of stop-finger 35 is cut away at its under side to allow the segment 36 to play freely within the limits set by the stop-projections 36—which at the extreme positions of the lever 32 engage the outer end of finger 35.

In bracket 40, preferably made integral with frame part 1, is journaled column stop-bar 41 by pins 42 which can revolve and move axially as well in bracket 40. On bar 41 are removably and adjustably fastened by means of its teeth 37 the column stops 43 by which in writing the space between the columns is determined. On the underside of bar 41 is secured lever arm 44 in a suitable place (Figs. 1, 2), the lever end of

which is pivotally connected to the upwardly bent rear end of shaft 25 (Fig. 1) by pin 45 and gently pressed against the head 47 of shaft 25 by spring 46.

The pivot 45 engages loosely in arm 44 to allow the latter to move column stop bar 41 axially in bracket 40 when lever 32 (Fig. 2) is moved circularly around its center, as well as to make an angular motion around pivot 42 from the normal position shown in Fig. 1 to that marked by dotted line C when shaft 25 is pushed 10 rearward by pressing knob 33. The arm 44 is of flat spring metal to allow the shaft or rod 25 to continue its rearward motion for reasons to be explained later on after it has, by shifting the arm 44 to or toward the dotted portion shown in Fig. 1, shifted the stop bar 43 15 angularly sufficiently to bring the tabulating stops into engagement as hereafter explained. It will be seen that bar 41 can be tilted on its pivot 42 from its normal position marked by dotted line N into that marked by dotted line D (Fig. 1). On frame part 1 (Fig. 1) is 20 secured in a suitable place stop 50 shown in full view in Fig. 2 provided with teeth (probably two or more in number) on its upper end adapted to engage in recesses 51, forming a locking rack on the underside of column stop bar 41, when the latter is tilted down as 25 described above and keeping thus bar 41 in this position from moving axially in either direction, thus transmitting the shock of impact of the carriage direct to the machine frame, and preventing rebound of the carriage. The form of recesses 51 is shown by a dotted 30 line in Fig. 1.

On top of carriage 8 Fig. 3 a single stop 52 is pivotally mounted in a suitable place by pivot screw 53 limited in its angular motion by stop-screws 54, 55 and pressed in its normal position shown in Fig. 3 against stop 54 35 by spring 56. Brackets 57 and 58 holding stop screws 54 and 55 respectively may be preferably integral with carriage frame 8. The end of stop 52 is suitably shaped as shown in Fig. 3.

The manner in which the tabulating device is operated is as follows: After the desired space between the columns has been set by inserting column stops 43 (Fig. 3) in their proper places on bar 41 the device is ready for column writing. It will be seen that the carriage 8, Fig. 1, held in place by rack 12 and pinion 10 40 connected by shaft 11 with an escapement of the well known kind commonly used in typewriters, will be released from pinion 10 when knob 33 is pressed to the left and cone 24 moving lever 23 as already described. At the same movement, but slightly earlier in time, 45 the inward movement of the shaft 25 will tilt column bar 41 into the position shown by dotted line D as also described before and thus cause the nose on the right side of the several column stops 43, Fig. 1, to come into the path of stop 52, engaging the toothed under surface 50 of the bar 41 at the same time with fixed dog 50. For reason of the two successive operations above mentioned 55 performed by the shifting motion of shaft 25, arm 44 is made of flat spring metal to allow the shaft to continue the shifting motion, as already described. During 60 the first part of this motion shaft 25 tilts bar 47 until it abuts against lock rack 50, described before, cone 24 being hereby so disposed on shaft 25 that it does not operate lever 23 yet. During the last part of the shifting motion of shaft 25, spring arm 44 yields enough to 65 allow cone 24 to operate. The carriage when released

is moved in the well known manner in the direction of the arrow, Fig. 3, to come to a stop as soon as stop 52 strikes one of the column stops 43 tilted in its path. When knob 33 is released shaft 25 will return to its normal position shown in Fig. 1, thereby first releasing 70 lever 23 from its cone 24 and causing carriage rack 12 to reengage in its pinion by pressure of spring 16 and the tilting bar 41 and stops 43 back to their normal position shown in Fig. 1. This will cause carriage 8 to stop on each line on these predetermined places 75 when knob 33 is pressed. As the spaces between the column stop 43, Fig. 3, are equal to the distances apart the writer wishes to have the decimal points of the different numbers—in one line, the carriage will stop when knob 33 is pressed for each column on the place 80 on which the decimal point has to come, provided the segment 36 in Fig. 2 has been set so that the decimal point notch stands opposite finger 35. After knob 33 is released each numeral written in the column will then be behind the decimal point. If now, for instance as shown in Fig. 2, segment 36 is turned so that notch 3 will stand opposite finger 35 bar 41 is moved at the same time by means of arm 44 to the right and stop 54 will strike column stop 43 three places—before the decimal point, so that after releasing knob 33 any 90 number written in this column will have three places before the decimal point.

The device shown in the drawings is provided with seven notches on segment 36 before the decimal notch showing that numbers with seven places before the 95 decimal point, can be written, but it can be readily seen that the device may be arranged for any desired number of places before the decimal point.

In Fig. 3 it will be seen that stop 52 in striking column stop 43 will be pressed against stop 55 and as soon as column bar 41 is tilted back into its normal position in which column stops 43 are clear of the path of stop 52, the latter will jump back by pressure of spring 56 to its stop 54, and be on the left side of stop 43. This enables the carriage to be fed along past the successive 100 tabulating stops, until the desired stop is reached, by successive pressures upon lever 32, without necessitating the striking of a type or space key to carry the carriage stop past the column stops.

Having thus described my invention what I claim 11 as new and desire to secure by Letters Patent is:

1. In a device of the character described, the combination of a carriage bearing a tabulating stop, a tabulating bar having a column stop and mounted on the machine frame so as to have longitudinal motion parallel with the 11 carriage movement and angular movement transverse thereto, an arm rigid with said bar, a journal oscillatory push rod or shaft mounted on the machine frame and having a crank arm connected to said arm on the tabulating bar, and an operating finger lever for said rod or shaft. 12

2. In a device of the character described, the combination of a carriage bearing a tabulating stop, a tabulating bar having a column stop and mounted on the machine frame so as to have longitudinal motion parallel with the carriage movement and angular movement transverse 11 thereto, an arm rigid with said bar, carriage escapement mechanism including a feed rack, a lever directly engaging said rack for disengaging it from the remaining escapement mechanism, an oscillatory push rod or shaft having a crank arm pivotally connected to said tabulating bar arm, and having a cam for operating said lever and a finger lever for its own operation and a finger secured to the machine frame for positioning and guiding the finger lever in several positions angularly disposed to each other. 12

3. In a device of the character described, the combination of a carriage bearing a tabulating stop, a tabulating bar having a column stop and mounted on the machine frame so as to have longitudinal motion parallel with the carriage movement and angular movement transverse thereto, a spring arm rigid with said bar, carriage escapement mechanism including a feed rack, a lever directly engaging said rack for disengaging it from the remaining escapement mechanism, an oscillatory push rod or shaft having a crank arm pivotally connected to said tabulating bar arm, and having a cam for operating said lever and a finger lever for its own operation, and a finger secured to the machine frame for positioning and guiding the finger lever in several positions angularly disposed to each other.

4. In a device of the character described, the combination of a paper carriage, a rack-bar pivotally mounted

thereon, a pinion engaging said rack-bar, a tabulating stop on the carriage, a tabulating bar having column stops and mounted on the machine frame so as to have longitudinal motion parallel with the carriage movement and angular movement transverse thereto, a spring arm rigid with said tabulating bar, a lifting lever for said rack-bar, an oscillatory push-rod or shaft having a finger lever for its own operation and a crank arm pivotally connected to said tabulating bar arm and having a cam operatively connected controlling said lifting lever and a stop on said rack-bar limiting its upward movement, whereby said lifting lever and rack-bar act as a brake to control the carriage movement.
